UNITED STATES PATENT OFFICE

166,066

BOTTLE OR SIMILAR ARTICLE

Walter E. Boschin, San Francisco, Calif., assignor to Glass Containers, Inc., San Francisco, Calif.,
a corporation of California

Application June 5, 1950, Serial No. 10,350

Term of patent 14 years

(Cl. D58—8)

To all whom it may concern:

Be it known that I, Walter E. Boschin, a citizen of the United States, residing in the city and county of San Francisco, State of California, have invented a new, original, and ornamental Design for a Bottle or Similar Article, of which the following is a specification, reference being had to the accompanying drawing, forming part thereof.

In the drawing:

Fig. 1 is a side elevation of a bottle or similar article, showing my new design;

Fig. 2 is a top view of said bottle.

I claim:

The ornamental design for a bottle or similar article, substantially as shown.

WALTER E. BOSCHIN.
